UNITED STATES PATENT OFFICE

113,998

DESIGN FOR A COMBINATION STOVE AND LAMP

Jesse Oliver Steele, Lund, Utah

Application June 16, 1938, Serial No. 77,892

Term of patent 14 years

To all whom it may concern:

Be it known that I, Jesse Oliver Steele, a citizen of the United States, residing at Lund, in the county of Iron and State of Utah, have invented a new, original, and ornamental Design for a Combination Stove and Lamp, of which the following is a specification, reference being had to the accompanying drawing, forming part thereof.

The figure is a perspective view of a combination stove and lamp, showing my new design.

The opposite sides of the stove and lamp are substantially the same as shown.

I claim:

The ornamental design for a combination stove and lamp, as shown and described.

JESSE OLIVER STEELE.
